DESIGN FOR A CONDIMENT DISPENSER

Glenn D. McCullough, Chicago, Ill.

Application May 23, 1946, Serial No. 130,008

Term of patent 14 years

(Cl. D44—22)

To all whom it may concern:

Be it known that I, Glenn D. McCullough, a citizen of the United States, residing at Chicago, in the county of Cook and State of Illinois, have invented a new, original, and ornamental Design for a Condiment Dispenser, of which the following is a specification, reference being had to the accompanying drawing, forming part thereof.

Fig. 2 is a side view thereof.

Figs. 3 and 4 are top and bottom views respectively thereof.

I claim:

The ornamental design for a condiment dispenser, as shown.

GLENN D. McCULLOUGH.
